(57) **CLAIM**

We claim the ornamental design for a material handling tool, as shown and described.

DESCRIPTION

FIG. 1 is a top perspective view of a material handling tool showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The ornamental design which is claimed is shown in solid lines in the drawings.

Any broken lines in the drawings are for illustrative purposes only and form no part of the claimed design.
